UNITED STATES PATENT OFFICE.

ARCHIE D. STANDEFORD, OF KANSAS CITY, MISSOURI.

SAFETY APPARATUS FOR MOVING-PICTURE MACHINES.

1,126,902.

Specification of Letters Patent.

Patented Feb. 2, 1915.

Application filed April 15, 1914. Serial No. 832,130.

To all whom it may concern:

Be it known that I, ARCHIE D. STANDEFORD, a citizen of the United States, residing at Kansas City, in the county of Jackson, son and State of Missouri, have invented certain new and useful Improvements in Safety Apparatus for Moving-Picture Machines, of which the following is a specification.

10 This invention relates to safety apparatus for moving picture machines, and it consists of automatic means to prevent combustion of films due to the projection of light thereon from a kinetoscope while said films are stationary or substantially so.

It is a well-known fact that films, being very combustible, are easily ignited by the light projected thereon from a kinetoscope should they stop or pile up in front of said light. So long as the films are traveling at normal speed past the light there is no danger, but should they break or their feed mechanism get out of order and result in their stopping in the light, then they are 25 quickly destroyed by ignition from said light.

By employing my mechanism all danger of the films burning is avoided, because accident to the films, or their feeding mechanism, instantly results in the automatic closing of a shutter which cuts off the light from the projecting machine.

In order that the invention may be fully understood, reference will now be made to 35 the accompanying drawing, in which:

Figure 1 shows the apparatus in operative position in a moving-picture machine. Fig. 2 is a front elevation of the projecting end of a kinetoscope provided with a shutter and other parts employed in carrying out the invention. Fig. 3 is a broken elevation of the film with certain parts of the apparatus adjacent thereto. Fig. 4 is a section, enlarged, on line IV—IV of Fig. 1. Fig. 5 40 is a diagram of the arc lamp circuit, and a communicating circuit constituting part of the invention. Fig. 6 is a diagram of the arc lamp circuit, and a communicating circuit constituting part of the invention.

A designates a projecting kinetoscope provided with the customary arc-lamp B.

50 C designates an upper magazine and D a lower magazine containing reels E and F, respectively.

G designates the film which travels from

the reel E to the take-up reel F, the latter being assisted in taking up the film by the 55 constantly driven feed-rolls H and the intermittently driven feed-roll I.

All of the foregoing mechanism is carried by a support J, and since it is in general use, further detailed description thereof is 60 deemed unnecessary.

1 designates a blower driven from the upper feed-roll H through the intermediary of a flexible shaft 2. Blower 1 has a blast-pipe 3 leading therefrom and communicating with a pair of nozzles 4 spaced equal distances from the film G, against the opposite sides of which they discharge blasts of air for a purpose which will hereinafter appear. One nozzle is arranged slightly 70 higher than its companion, so that the currents discharged therefrom may cross without interference, as indicated by dotted lines K, should an accident cause the film to move out of the path of said currents. 75

5 designates a self-closing switch located at the opposite edge of the film from the nozzles 4 and pivotally mounted at its upper end in a housing 6, having an opening 7 adjacent the film to admit blasts from the 80 nozzles 4.

Housing 6 is mounted upon a block of fiber or other insulating material 8, supporting a contact 9 adapted to coact with the switch 5 in closing a circuit 10, communicating with the arc-lamp circuit 11. 85

12 designates a self-closing shutter-pivotally-mounted upon a bracket 13 secured to the projecting end of the kinetoscope A to cut off the light projected from the latter 90 when said shutter closes. The closing movement of the shutter is checked by a stop 13^a extending from the bracket 13.

Shutter 12 is normally held in open position by a latch 14 pivotally-mounted upon 95 a bracket 13 and engaging a shoulder 15 on the shutter.

The lower end of the latch 14 is provided with an armature 16, adapted to be attracted by an electromagnet 17, carried by the 100 bracket 13 and arranged in the circuit 10.

Operation: So long as the film G is being taken up properly by the reel F, it remains in the path of the two currents of air discharged from the nozzles 4, and thus deflects 105 said currents against the switch 5, so that

the same will be held in open position. Should the film break or the take-up reel F fail to properly perform its function and allow the film to pile upon the platform J 5 and out of the path of said air currents, the switch 5 drops to closed position against the contact 9 and closes the circuit 10, which energizes the electromagnet 17 and attracts the armature 16. As the armature 16 moves 10 toward the electromagnet 17, the latch 14 is disengaged from the shoulder 15 of the shutter 12, so that the same will drop upon the stop 13^a and shut off the light from the kinetoscope A, thereby avoiding all danger 15 of the film becoming ignited from said light.

Should the operation of the film feeding mechanism become interrupted through the interruption of the circuit 11, or from any other cause, the blower 1 will stop by reason 20 of its driving connection with said film feeding mechanism through the intermediacy of the shaft 2. Stoppage of the blower 1, of course, stops the air current, so that switch 5 is permitted to swing against the contact 9 25 and close the circuit 10, whereby the shutter 12 is permitted to close, as above described.

When the shutter 12 is to be again opened, the film feeding mechanism is started up and the switch 5 is opened by the air currents as before. The opening of switch 5 de- 30 energizes the magnet 17, so that the same will not disengage the latch 14 from the shutter when the same is opened, until the air currents are again interrupted.

35 When it is desired to close the shutter 12 without closing the switch 5, the circuit 10 is manually closed to energize the electromagnet 17, by closing a switch 19.

40 Automatic closing of the shutter 12 may be avoided when desired, by manually opening the circuit 10 through a switch 20.

By automatically closing the shutter 12 through means controlled by the film feeding mechanism, it is obvious that said 45 shutter will be closed immediately on the occurrence of an accident to said feeding mechanism, and hence all danger of burning the films is obviated.

Having thus described my invention, what

I claim and desire to secure by Letters 50 Patent is:

1. The combination with a projecting machine, a film and its feeding mechanism, of a self-closing shutter to cut off the light from said projecting machine, a latch to 55 normally hold said shutter open, a circuit embodying means to release said latch from the shutter, and air-controlled means to normally hold said circuit open.

2. The combination with a projecting machine, its circuit, and a film arranged in front of said projecting machine, of a shutter to cut off the light from said projecting machine, an electromagnet for controlling said shutter, a second circuit communicating 65 with the first circuit to energize said electromagnet, and air-controlled means to normally hold the second circuit open.

3. The combination with a projecting machine, and a film arranged in front of said 70 projecting machine, of a shutter to cut off the light from said projecting machine, a circuit for controlling said shutter, and an air-controlled switch to control said circuit.

4. The combination with a projecting machine, and a film arranged in front of said projecting machine, of a shutter to cut off the light from said projecting machine, a circuit for controlling said shutter, a self- 75 closing switch to control said circuit, and nozzles to direct air blasts against opposite sides of the film to normally hold said switch open.

5. The combination with a projecting machine, and a film arranged in front of said 80 projecting machine, of a shutter to cut off the light from said projecting machine, a pair of nozzles arranged to discharge blasts against opposite sides of the film, a switch 85 against which the air blasts are deflected by the film, and a circuit controlled by said switch for controlling the shutter.

In testimony whereof I affix my signature, in the presence of two witnesses.

ARCHIE D. STANDEFORD.
